CLAIM

The ornamental design for a rotary aperture, as shown and
described.

DESCRIPTION

FIG. 1 is a front top perspective view of the rotary aperture.
FIG. 2 is a rear bottom perspective view thereof.

FIG. 3 is a right side elevation view thereof.

FIG. 4 is a rear side elevation view thereof.

FIG. 5 is a front side elevation view thereof.

FIG. 6 is a left side elevation view thereof.

FIG. 7 is a top plan view thereof; and,

FIG. 8 is a bottom plan view thereof.

The dot-dot-dash broken lines denote the boundary of the
claimed design.

The dot-dot-dot broken lines illustrate environmental fea-
tures and form no part of the claimed design. The broken
lines form no part of the claimed design.

1 Claim, 7 Drawing Sheets
